ATTORNEY

UNITED STATES PATENT OFFICE.

WILLIAM SPEITEL, OF NEW YORK, N. Y.

DESIGN FOR A PAPER-CUTTER OR SIMILAR ARTICLE.

52,105.

Specification for Design.

Patented June 11, 1918.

Application filed March 7, 1918. Serial No. 221,077. Term of patent 3½ years.

To all whom it may concern:

Be it known that I, WILLIAM SPEITEL, a citizen of the United States, residing at New York city, in the county and State of New York, have invented a new, original, and ornamental Design for a Paper-Cutter or Similar Article, of which the following is a specification, reference being had to the accompanying drawing, forming part thereof.

I claim:

The ornamental design for a paper cutter or similar article, substantially as shown.

WILLIAM SPEITEL.
